UNITED STATES PATENT OFFICE

2,610,579

SILK SCREEN PRINTING PRESS

Charles A. Wing, Ann Arbor, Mich.

Application December 9, 1949, Serial No. 132,129

18 Claims. (Cl. 101—123)

1

This invention relates to silk screen printing presses, and more particularly to an automatic silk screen printing press which is pneumatically operable and is adapted for the screening of any flat material such as paper, show cards, card-board, wood, metal or cloth.

The present invention provides a base upon which is mounted a suitable silk screen support, there being arranged upon the silk screen mounted on such support, and upon its under surface a suitable stencil. There is also provided a suitable stationary vacuum pad or work piece support on to which a card or other work piece is transported by the work slide. The work piece has a screening position as well as a discharge position, and furthermore has a pre-load position upon the base of the machine. The work slide is adapted by suitable grippers to engage the work piece so that movement of the work slide in one direction will transfer the work piece to the vacuum pad or work piece support, after which the grippers will automatically release the work piece. A suitable squeegee is carried by the work slide and is adapted upon the return movement of the work slide to bear upon the top surface of the screen and transfer there-through printing material upon the work piece through a stencil upon said screen. Upon the next transferring movement of the work slide the aforesaid pair of grippers engages the next work piece in its pre-load position and at the same time a second set of grippers engage the work piece or card upon the vacuum pad so that as the new work piece or card is transferred to the work piece support, the first work piece is transferred to discharge position.

It is the object of the present invention to provide a continuously operable printing device wherein the work slide is intermittently reciprocating with respect to the machine base for transferring work sheets to printing position, simultaneously ejecting the previously printed work piece, and upon the return stroke of the work slide screening the work piece to obtain a print thereon corresponding to the stencil upon the screen.

It is the further object of this invention to provide a simple compact mechanism which will operate with the maximum efficiency for screening work sheets continuously.

These and other objects will be seen from the following specification and claims in conjunction with the appended drawings in which:

Fig. 1 is a right side elevational view of the machine.

2

Fig. 2 is an end elevational view thereof broken away and sectioned on line 2—2 of Fig. 1.

Fig. 3 is a fragmentary partially broken away elevational section illustrating the construction of the pneumatic cylinder which operates the work slide of the machine.

Fig. 4 is a partially broken away elevational section illustrating one of the work piece grippers and one of the screen frame adjustable locators.

Fig. 5 is an elevational view of a squeegee sharpener construction.

Fig. 6 is an enlarged section on line 6—6 of Fig. 5.

Fig. 7 is a fragmentary plan view of the left end of the machine shown in Fig. 1 illustrating the locators for the work piece in pre-loading position.

Fig. 8 is a fragmentary side elevational view illustrating the construction of the operating mechanism for the adjustable locators.

Fig. 9 is a diagrammatic view illustrating the work slide cylinder, the vacuum operating cylinder, the four-way controlling valves and the various pilot valves together with their pneumatic connections.

Fig. 10 is a plan view of the screen support and screen assembly, partially broken away and sectioned to illustrate one of the adjustable locators upon said screen assembly.

Fig. 11 is a partially broken away plan view of the machine.

Fig. 12 is a fragmentary elevational view of that portion of the machine shown in Fig. 11, being the opposite side of the machine shown in Fig. 1.

Fig. 13 is a fragmentary plan view of the machine illustrating the work slide at the end of the work piece transferring stroke, also illustrating the construction of the retractable locator actuating bar.

Fig. 14 is a fragmentary elevational view thereof which also illustrates the cam arm associated with the squeegee holder and the spring loaded detent upon the work slide which holds the squeegee in cammed up position on and during the work piece transfer stroke.

Fig. 15 is a section taken on line 15—15 of Fig. 11 and illustrating the positioning of the squeegee at the end of the return screening stroke as it engages screening material before it is cammed upwardly for the next successive work piece transferring stroke.

Fig. 16 is an elevational section illustrating the construction of four-way valve 107 shown in Fig. 9.

Fig. 17 is a diagrammatic section illustrating the construction of the control valve 113.

Referring to the drawings, the silk screen printing press includes a base 11 with hollow interior 12 to contain the various valve mechanisms and other pneumatic mechanisms hereinafter described, there being provided upon one side a removable valve chamber cover 13 as shown in Fig. 1.

The base 11 includes the horizontal platform 14 and the inclined instrument panel 15 with operating lever 16 thereon hereinafter further described. Spaced upright piston rod supports 17 and 18 extend upwardly from the base 11 upon one side of the machine to cooperatively receive and secure the respective opposite ends of hollow stationary piston rod 19.

Pneumatic cylinder 20 with spaced cylinder heads 21 and 22 at its opposite ends is reciprocally mounted upon piston rod 19 and transversely arranged work slide 23 is secured to cylinder 20 between the cylinder heads 21 and 22 as shown in Fig. 1. Thus the cylinder 20 supports the work slide 23 upon one longitudinal edge for reciprocal movements relative to the bed 14 of the machine. The roller or rollers 24 depend from the opposite side of work slide 23 and cooperatively bear upon the guide supporting strip 25 arranged longitudinally on the machine bed 14. Thus the work slide operating upon the stationary piston rod 19 is guided and supported upon one side so that reciprocal movements thereof are guided by a single member, and it is possible to swing the entire work slide upwardly around the piston rod to facilitate inspection of the underside of the work slide or that portion of the machine bed normally underneath the work slide.

Transverse journals 26, 27 and 28 are formed within work slide 23, and with suitable bushings 29 therein there is provided a transverse support for the trunnion bar 30 permitting rotary movements thereof. Transverse cam arm 31 depends from the outer end of trunnion bar 30 and is secured thereto at 32, said bar having centrally mounted thereon within the workslide 23 the squeegee holder 33 shown in Figs. 1 and 2.

Hollow rectangular vacuum bed 34 is centrally mounted upon machine bed 14 and includes hollow vacuum chamber 35, the top surface 37 of the vacuum bed having formed therein a plurality of small openings 36. With the work sheet properly positioned upon vacuum bed surface 37 vacuum may be applied to the under surface thereof through the upright passage 38 of the vacuum bed which terminates in the vacuum chamber 35. Suitable vacuum producing mechanism forms a part of the printing machine hereinafter to be described, and it is contemplated that a suitable pipe will establish vacuum communication to the passage 38, as illustrated in Fig. 9 of the drawings hereinafter described.

Hollow screen support 39 including horizontal flanges 39' as shown in Figs. 2 and 10 is effectively secured and positioned above the machine bed 14 providing a mounting for the rectangular screen support 40, across the lower surface of which extends a silk screen 41 to which is secured a stencil of the desired configuration.

Four work sheet gripper units 42 are arranged in pairs depending from the leading and rear edges of work slide support 23 as shown in Figs. 1 and 2, each of said grippers including a pivotal lower work sheet engaging arm 77, hereinafter described in detail in conjunction with the detailed description of Fig. 4.

A pair of spaced adjustable sequence cams 44 and 44' depend from work slide 23 for controlling certain pilot valves hereinafter described with respect to Fig. 9 for achieving the cycle of operations to be described, said sequence cams being laterally spaced as in Fig. 2, and longitudinally spaced as shown in Fig. 1.

There is also shown in Fig. 2 an interference cam 45 hereinafter to be described but which under certain conditions is cooperatively engageable with the cam arm 31 for camming up the squeegee carried by the squeegee holder 33 to elevate the same with respect to the top surface 37 of the work piece supporting vacuum bed, as where no work piece has been positioned thereon.

Referring to Fig. 3 there is shown in enlarged partially sectioned detail one end of the pneumatic cylinder 20 including the spaced cylinder heads 21 and 22 which is reciprocally movable upon the hollow piston rod 19 whose respective opposite ends extend into the piston rod supports 17 and 18, the latter of which is shown in Fig. 3. Spaced air line pipes 24' and 25' shown in Fig. 1 project upwardly from the interior 12 of the machine while their upper ends join the ends of hollow piston 19, air line 24' being also shown in Fig. 3.

The cylinder heads 21 and 22 are machined at 46 to receive therebetween the work slide 23 which is secured thereto for movement in unison with the reciprocal movements of cylinder 20 which interconnects said cylinder heads.

The disc 47 is suitably secured around the end portions of piston rods 19 and is secured to the respective piston rod supports 17 and 18 as by the bolts 48. The piston rod includes a central portion of slightly increased diameter 49 from the opposite ends of which project the hollow tubular elements 50 whose exterior diameter is slightly less than the interior diameter of the piston rod 19. As shown in Fig. 3 the tubular elements 50 project into the inner ends of piston rod elements 19 and are secured thereto as by the hollow transverse rivets 52.

Air line pipe 25' at its inner end at point 51 is threadably joined to tubular element 50 which forms a part of piston rod 19 so that compressed air through the interior 51' of tube 50 communicates with the interior of rivet 52 through the opening 53, the opposite ends of which are in communication with annular air chamber 54 arranged upon one side of the piston to be described. Said air chamber is bounded upon one end by the annular pressure seal 55 which is retained by the gland 56 and the guide bushing 57. Wiping ring 58 is also retained within an annular recess in gland 56 for surface engagement with piston rod 19, whereas said gland 56 is secured to cylinder head 22 as by the bolts 59.

Cylinder 20 is a double acting cylinder movable upon the fixed piston rod 19. The compressed air for the cylinder is piped in from each end to points on either side of the piston, one of which is shown in detail in Fig. 3 corresponding to cylinder head 22.

The piston for said cylinder includes spaced hardened rings 60 which are separated by a shoulder upon the piston rod mid section 49, said rings serving as a support for the cup washers 61 having the ring 62 interposed therebetween. The piston assembly is secured together by a plurality of bolts 63 one of which is shown in Fig. 3.

The hardened ring plates 64 are set into the cylinder head counterbore and are adapted to

contact the piston assembly for limiting the cylinder stroke. The inside diameter of these ring plates, one of which is shown in Fig. 3, closely fit the enlarged diameter of piston rod mid-section 49 to develop the cushioned effect at each end of the cylinder stroke.

Cylinder head 22 is provided with an external port 65 which communicates with the interior of stationary piston rod 19 and the outer end of the port or passage 65 is adapted for connection to one end of the hydraulic cylinders or pneumatic cylinders of each of the four gripper units hereafter described in detail.

Passage 66 in cylinder head 22 is joined at one end to the pressure chamber 54 and is adapted for communication with the horizontal passage 67 which delivers pressure fluid, in this case compressed air to the space between piston 60 and the ring plate 64 shown in Fig. 3. However ball relief valve 68 is positioned at the end of passage 66 and retained by the spring 69 so that compressed air in chamber 54 will first be delivered out through the port 65 for actuating all of the gripper units before movement of the cylinder is effected. Thus this ball relief valve acts as a restriction until the four gripper units are closed, after which the air pressure continues to build up until air escapes past ball relief valve 68 and into passage 67 for initiating movement of the cylinder 20 to the right.

After the cylinder has moved sufficiently far to allow ring plate 64 to pass over the enlarged mid-section 49 of the piston rod, air is allowed to pass through to the piston face between ring plate 64 and the normal piston rod diameter. This construction allows the closing of the work sheet gripper units prior to the start of the work slide cylinder stroke and further provides an accelerated start for the work slide cylinder 20.

Ball relief valve 68 can be adjusted by regulating the compression of spring 69, and this is effected by adjusting the threaded stem 70 which bears against said spring.

Transverse opening 71 is formed within the ring plate 64 in conjunction with a pressure sealed cone point 74 of the screw 75 to thereby provide an adjustment of the cushion effect between the piston 60 and ring plate 64 above described. Air return through passage 71 on the opposite stroke of cylinder 20 is blocked by the spring loaded ball valve 73 which seats into a countersink in ring plate 64.

The identical construction, less the external port 65 to the gripper units is also provided in the left cylinder head 21, and this detail is not repeated or further described.

Referring to Fig. 4 one of the pneumatically operated four work sheet gripper units 42 is shown in detail, each of said units being suitably secured upon the underside of the work slide 23 being arranged at its opposite ends and upon its opposite sides as shown in Figs. 1 and 2, said gripper units being adapted to engage the work sheet at its leading edge for moving the same from the pre-load position 76' Fig. 1 to the screening position 76''. The other set of gripper units which are mounted upon opposite sides of the leading portion of the work slide are adapted to also engage the leading edge of the work sheet as it rests upon the vacuum bed for moving or ejecting the work sheet from the screening position to the discharge position 76''' indicated in Fig. 1.

Now referring to Fig. 4 the gripper unit 42 includes the upper fixed jaw 79 which is adapted

to traverse horizontally during work slide travel between the underside of the screen 41 and the top of the work sheet 76. Lower grip 77 with interchangeable gripping pad 78 is adapted to bear against the underside of the work sheet at one end and is pivotally mounted at 80 to a portion of the work slide 23.

Pneumatic cylinder 81 depends from work slide 23 and into the gripper housing 42 said cylinder having a nipple 82 at its upper end to which is connected the pipe 83 joined to the exterior port 65 from cylinder head 22 to thereby conduct compressed air to the interior of cylinder 81. Reciprocal piston 84 is positioned within cylinder 81 and projects therefrom and through a corresponding opening in the gripper housing 42, with the outer end of said piston engaging lower gripper arm 77 at point 85. Upright pin 86 is adjustably secured at one end 88 to the opposite end of gripper arm 77 and carries a piston 87 at its upper end which is reciprocal within a corresponding opening 87' within gripper housing 42. A coil spring 89 is interposed between piston 87 and the housing 42 so that upon fluid pressure release of piston 84 the spring 89 under initial compression will return the piston 87 upwardly thus causing a downward opening movement of the lower jaw 77 of the work sheet gripper mechanism.

It is contemplated that in the operation of the machine that all four of the gripper units are energized simultaneously from the exterior pressure port 65 from the cylinder head 22. Furthermore all of the gripper units will be released simultaneously when the source of compressed air to pipe 65 is cut off in the manner hereafter to be described.

In operation the pair of gripper units at the rear edge of the work slide engage the work sheet in its pre-load position so that subsequent movement of the cylinder 20 to the right carries the work sheet to the vacuum bed 34. This is the transferring stroke of the work slide. At the end of this stroke the grippers are released so that on the return movement of the work slide the work sheet remains upon the vacuum bed as the squeegee 154 hereafter described bears down upon the silk screen 41 transferring screening material through the screen and the stencil thereunder printing upon the work sheet which is retained upon the vacuum bed as the squeegee is traversed from right to left over the surface thereof.

At the end of the screening stroke of the work slide the squeegee is cammed upwardly in a manner hereafter described, and the gripper units at the rear end of the work slide again close upon the next work sheet in its pre-load position 76'. As the work slide moves to the right now on its transferring stroke it is apparent that the new sheet will be carried over to rest upon the vacuum bed. Prior to this movement however, at the same time as said rear grippers engage the leading edge of the second work sheet, the pair of grippers at the forward end of the work slide simultaneously engage the leading edge of the first work sheet. Consequently the first sheet is withdrawn from the vacuum bed at the same time as the next sheet is delivered thereto. In other words the rear grippers engage the sheet to move the same i. e. transfer the same to the vacuum pad, whereas the forward set of grippers are employed to engage the previously printed work sheet to remove the same from the vacuum

pad to the discharge area 171 shown in Fig. 12 hereafter to be described.

Now referring to Fig. 7 of the drawings the loading platform for the machine is generally designated by the numeral 90, and the work sheet 76 has been positioned thereon with its leading edge in the pre-load position designated by the arrow 76' of Fig. 1.

Locator 91 is arranged upon the machine bed 14 adjacent the loading platform 90 so as to receive thereunder the leading edge of the work sheet 76, the end portion of said sheet bearing against the upright portion 91' of said locator. A pair of vertically adjustable locator pins 92 with rack gears 93 thereon are arranged for vertical reciprocal movement and are adapted to assume the elevated position shown in Fig. 8 to thereby engage the leading longitudinal edge of the work sheet 76.

Rotatable shaft 95 carries a pair of spaced pinions 94 which are in mesh with the rack gears 93 upon the two locator pins 92, said pins and said pinions being positioned within suitable housings 94' in the bed 14. Lever arm 96 is secured upon the outer end of shaft 95 and is arranged transversely thereof so that a rocking movement of arm 96 in one direction or the other will effect reciprocal movement of the locator pins 92. Transverse opening 97 at the upper end of arm 96 is adapted for attachment to longitudinally reciprocal or retractable locator operating bar 176 which is illustrated in Figs. 13 and 14 of the drawings.

Connector 177 is pivotally joined at 178 to the upper end of the arm 96, the opposite end of the bar 176 extending loosely through an opening in the stop 179 which depends from work slide 23. Adjustable stop 180 is secured to one end of the bar 176, and a coil spring 181 is mounted upon bar 176 and interposed between stops 179 and 180. A second adjustable stop 182 is secured upon the bar 176 in spaced relation to the stop 180 so that when the work slide 23 traverses to the right from the position shown in Fig. 14 eventually the movable stop 179 will bear against stop 182 translating the rod 176 to the right sufficiently to cause a retraction of the locators 92 shown in Fig. 7. By this arrangement the next sheet to be transferred to printing position, having been previously properly located by locators 91 and 92, is now free to be drawn from the pre-load position shown in Fig. 7 with locators 92 dropped down and out of the way.

From the illustration in Figs. 13 and 14 it is apparent that as the work slide reaches the position shown in Fig. 14 in completing the work sheet transferring stroke, the movable stop 179 will exert a thrust upon the rod 176 to the left through the agency of the coil spring 181. This has the effect of rocking the arm 96 which regulates the locators 92 so that the same will be elevated to the position shown in Fig. 8. Thus the locators 92 in cooperation with locator 91 are ready to effect the proper positioning of the next work sheet upon the loading platform 90 to assure that the same will be properly engaged by the grippers 42 at the rear end of the work slide 23 for the next work sheet transferring stroke. By this construction it is apparent that the locators 92 will be elevated to locating position just after the preceding work sheet has been transferred thereover into printing position upon the vacuum bed. As shown in Fig. 7 a work sheet hold down clip 98 is also arranged upon machine bed 14 upon the opposite side of the

loading platform 90 for cooperation with the corresponding hold down element 91 which forms a part of the locator 91-91'.

Referring to Figs. 10, 11 and 12 there are shown a pair of spaced horizontally extending printing screen supporting angle plates which include the horizontal portions 39' and the upright portions 147. The respective opposite ends of said angle plates have legs 148 which are secured upon the bed 14 and arranged in the manner shown in Figs. 11 and 12. The printing frame support also includes the transverse upright screen support 39 whose respective opposite ends lie between angle members 147 and whose lower edge bears upon and is suitably secured to horizontal flange elements 39'.

Thus the silk screen frame 40 is adapted to rest upon the angle iron elements 39' along its longitudinal edges, whereas the leading edge of the screen frame is arranged adjacent the cross piece 39.

Referring to Fig. 10 there are three locator buttons 99 two of which are mounted upon angle iron 147 and one of which is centrally arranged upon the transverse bar 39. There are similarly mounted upon the screen frame 40 three adjustable locators which are adapted to cooperatively engage the three locator buttons as shown, one of said locators being shown in section in Fig. 10, and also illustrated on an enlarged scale in Fig. 4.

Transverse bushings 100 are positioned through the screen frame 40 and secured in position by the nuts 101. Locator pins 102 are threaded through said bushings, a suitable lock nut 104 being provided for securing locator pin 102 in a predetermined adjusted position. Said pin has a head 103 thereon by which the same may be rotatably adjusted. Once the locators have been properly adjusted it is apparent that there will then be a predetermined positioning of the screen frame 40 upon its support 39'. Thus should the screen frame be temporarily removed, as where a second screen is employed in the machine, then there is the assurance that when the first screen is replaced it will occupy the same relative position it originally had with respect to its support as well as with respect to the vacuum bed upon which a work sheet is positioned.

Very often there will be a plurality of screen sets as where multiple colors are desired to be printed upon the work sheet, and in that case it is desirable that the locators of each of the screen frames be so adjusted that there will be proper registry between the respective screens when they are placed upon the screen support 39'. Generally there is employed a separate unit for the pre-registration of screen sets which does not purport to be a part of the present invention. However a suitable illuminated stand is provided similar to the commonly known tracing table. There is provided work sheet locating points as well as screen locating points which are identical with the locator buttons 99 shown in Fig. 10. In use a translucent work sheet is located upon the glass of the pre-registration unit and the first pass screen adjusted to laterally position and properly locate the impression relative to the work sheet. The adjustment is obtained by means of the three adjustable locators 102 on the screen frame 40 shown in Fig. 10. The first impression is transferred to the work sheet with suitable screening material by means of a manually operated squeegee. The remaining screens in the set are then interchanged in the

pre-registration unit. By adjusting the three locators on each screen, each screen can be accurately registered with the initial screen and with one another. These pre-registered sets of screens can then be loaded directly upon the screen support 39' with respect to the locating buttons 99 without further registration for the different screening passes.

As shown in Fig. 10 a wedge lock 105 is interposed between the screen frame 40 and the flange 147, and said lock is expanded by means of the screw element 106 to thereby effectively secure the screen frame 40 upon its supports 39' in proper pre-registered position.

There is shown in Fig. 9 a diagrammatic illustration of the work slide cylinder 20 illustrating the adjustable sequence cams 44 and 44' mounted thereon. Normally and as shown in Fig. 2 said cams depend from the lower side of work slide 23 however they are shown for purposes of illustration as mounted upon the cylinder 20 as it will be remembered that the work slide is secured to the cylinder 20 for movement in unison.

A vacuum operating cylinder 119 is shown connected to a vacuum cylinder 125 and there is provided four-way valve 107 for controlling the flow of compressed air to one end or the other of cylinder 20, and a second four-way valve 108 adapted for regulating the flow of compressed air to one end or the other of a vacuum operating cylinder 119. There are also shown a plurality of pilot valves 132, 135, 137 and 140 which are interconnected with the respective four-way valves 107 and 108 in the manner now to be described.

Fig. 16 illustrates the detail of construction of the four-way valve 107, and its construction is identical with four-way valve 108, both of said valves including a coil spring 109 which normally urges the movable valve element within the four-way valve to one extreme position. The valve element is moved in the opposite direction by compressed air, though hydraulic fluid could be employed in the present mechanism.

Compressed air pipe 110 may be joined to an exterior source of compressed air or on the other hand the compressed air source may be mounted within the machine base and connected to said pipe. Shut off valve 111 is arranged upon pipe 110 and there is also provided a start and stop operating lever 16 which is mounted upon the instrument panel as shown in Fig. 11 and which is joined to and controls the two way valve 113 which is shown in detail in Fig. 17. In one position of control lever 16 the valve element within the valve 113 is moved to the right permitting the flow of compressed air from pipe 110 out through delivery pipe 114. In another position of lever 16 the valve element is so moved as to establish communication between delivery pipe 114 and an exhaust port 114' so that in effect the system will be bled whenever the supply of compressed air is cut off through operation of the lever 16.

Pipe 114 is joined at its outer end to the central port of the four-way valve 107 as illustrated in Fig. 16. Similarly there is a branch pipe 115 which delivers compressed air to a corresponding central port of the four-way valve 108. A third branch pipe 116 interconnects pipe 114 with the normally closed pilot valve 140, the pipe 116 continuing from said pilot valve for connection to one end of the four-way valve 108.

There is another branch pipe 129 in which there is interposed manually controlled two-way valve 131 which valve is opened by operation of the foot pedal 130 shown in Figs. 1 and 2. For auto-

matic operation of foot pedal 130 may be secured in depressed position by means of the latch 130'. The pipe 129 is joined to pilot valve 132, and a second extension pipe 133 interconnects pilot valve 132 with the opposite end of four-way valve 107 as illustrated in Fig. 16. There is also a branch pipe 134 which interconnects pipe 133 and the normally closed pilot valve 135, the latter having extending therefrom a suitable exhaust pipe 136.

Exhaust pipes 118 and 122 extend from four-way valves 107 and 108 and are connected to the exhaust muffler 119 as shown. In Fig. 9 pilot valve 137 is open due to engagement of the sequence cam 44 therewith so that compressed air in pipe 116 can escape through pipe 139, through the pilot valve 137 and out through the exhaust pipe 138. When the lever 16 is turned to open position compressed air is delivered to pipe 129 and if the pedal 130 is depressed the fluid will flow through pilot valve 132 which is open and thence through pipe 133 to the end of four-way valve 107 causing the valve element therein to move to the right of the position shown in Fig. 16. The compressed air will then flow through the four-way valve and out through the pipe 24' and into the cylinder 20 upon the right side of its stationary piston 60.

As previously described in detail the compressed air is first available through the exterior port 65 which connects each of the gripper units 42 for closing the same. After the pressure builds up the ball valve 68 Fig. 3 will open and the compressed air will flow into the cylinder causing movement to the right which corresponds to the workpiece transferring movement of the work slide of the machine. And the cylinder will continue until it reaches the limit of its movement to the right. However before this occurs the sequence cam 44' will engage and open the pilot valve 140 and this will permit the flow of compressed air to the four-way valve 108 for operating the same in exactly the same manner as four-way valve 107 above described. It will be noted that sequence cam 44 has moved away from pilot valve 137 so that the exhaust pipe 139-138 is closed.

The four-way valve 108 is now set so that compressed air delivered through the pipe 115 will flow through pipe 118 to the left side of vacuum operating cylinder 119 which contains piston 120 and piston rod 123 connected thereto. Exhaust from the opposite side of piston 120 returns to four-way valve 108 through the pipe 121 and exhausts therefrom through the exhaust pipe 122.

At the same time while cylinder 20 is moving to the right exhaust fluid from the opposite side of piston 60 is returning through pipe 25' to four-way valve 107 and exhausted therefrom through the pipe 118. It will be noted that flow control adjustable valves 117 are arranged in the cylinder lines 24' and 25' whereby the speed of movement of cylinder 20 can be regulated.

Piston rod 123 has upon its opposite end a vacuum inducing piston 124 which reciprocates within vacuum cylinder 125, and it will be seen that the movement to the right of piston 120 effects a corresponding movement of piston 124 creating a vacuum upon the left side of piston 124, and this vacuum is communicated to the vacuum bed 34 by the pipe 126. In the cycle of operation it is apparent that after cylinder 20 completes its transferring stroke to the right during which a work sheet has been moved into position upon the vacuum bed 34, then the vacu-

um circuit through the pipe 126 is energized to effectively retain the work sheet in position upon said bed during the return printing stroke of the cylinder 20 to the left. It will be noted that as soon as pressure fluid is cut off from the right hand end of cylinder 20 it will also be cut off from the pipe 65 which leads to the gripper units so that these will all be released so that there will be no interference of the work sheet with the return to the left of the work slide.

A cam 128 is mounted upon piston rod 123 and in Fig. 9 is shown in engagement with pilot valve 132 opening the circuit therethrough so that pressure fluid was available in pipe 133 for operating four-way valve 107. However as soon as piston 120 moves to the right in sequence to the right hand movement of cylinder 20 cam 128 will be disengaged from pilot valve 132 and the flow therethrough stopped. As soon as cam 128 engages pilot valve 135 opening the same it is apparent that pipe 133—134 will exhaust the fluid from four-way valve 107 through the exhaust pipe 136, thus causing an automatic spring operated reversal of four-way valve 107.

As shown in Fig. 16 this reversal directs pressure fluid from pipe 114 to cylinder pipe 25' initiating the return screening movement to the left of cylinder 20, and now the exhaust from the other side of said cylinder returns to four-way valve 107 through pipe 24'.

Now as cylinder 20 returns to the position shown in Fig. 9 sequence cam 44 again opens the pilot valve 37 permitting fluid to exhaust therethrough, and this causes an automatic reversal of four-way valve 108 due to the action of its spring 109. Then the pressure fluid in pipe 115 is delivered to the right end of vacuum operating cylinder 120 through the pipe 121, and this causes movement of its piston 120 back towards the position shown in Fig. 9, releasing the vacuum in pipe 126 and consequently releasing the work sheet 76 from the vacuum bed 37. Thus it appears that at the end of the leftward screening movement of the work slide and cylinder 20, the work sheet will be automatically released so that upon the return transfer movement of said work slide to the right the leading grippers will engage said work sheet and eject the same onto the discharge area 171 Fig. 12.

At the same time that vacuum is released in pipe 126 it is apparent a vacuum condition is created upon the right side of piston 124 and this vacuum will be transmitted through the pipe 127, pipe 141 to the vacuum operated automatic loading mechanism diagrammatically indicated at 142 and having the loading arm 143 which is so constructed as to pick up the top sheet from a stack of work sheets and transfer the same to the loading platform 93 of Fig. 7. There is also provided a branch pipe 144 connected to an automatic vacuum operated work piece pick off mechanism 145 with operating arm 146 which is adapted to remove the printed sheet from its discharge position 76''' indicated in Fig. 1.

The structure of the vacuum operated automatic loading and pick off mechanism form no part of the present invention and therefore further description thereof is omitted. It will be noted however that both units 142 and 145 will be operated simultaneously.

The present printing machine operates upon a step cycle in that the vacuum operating cylinder 119 actuates the control for the work slide cylinder 20, and the latter actuates the control for the

vacuum operating cylinder 119. This arrangement insures exactly repetitive cycling and eliminates any necessity for further coordinating the relative movements of the two cylinders.

5 A further merit in this instance is that the step cycle arrangement allows the work slide cylinder to continue on to the fixed end of its stroke as necessary for the successful operation of the printing unit, after tripping the pilot valve 108 which actuates the control valve 103 for vacuum operating cylinder 119. It will be noted that vacuum cylinder 125 provides two difference circuits, only one of which is used for the vacuum bed 34. The remaining circuit can be applied 10 to the vacuum requirements of the automatic loading and pickoff mechanisms 142 and 145. Vacuum is developed in this extra circuit before 15 the work sheet transfer stroke during which stroke the next work sheet would be moved to 20 preload position or pickoff from the discharge area.

Referring to Figs. 11 and 12 there is provided upon the bed 14 the stop 149 with adjustable pin 150 projecting therefrom, and including the lock nut 151 for setting said pin in adjusted position. As shown in Figs. 11 and 12 there is a second 25 stop 152 spaced from stop 149 including stop pin 153 and lock nut 151. The stops 149 and 152 are arranged so as to be in the line of travel of 30 the knock-off or cam arm 31 which extends from the trunnion shaft 30 upon which the squeegee holder 33 is mounted. It is the purpose of the stops 150 and 153 to intermittently engage the lower end of the cam arm 31, with 35 cam arm 31 engaged by the stop 153 at the end of the travel of the work slide 23 so that the squeegee is cammed upwardly out of engagement with the screen 41 for the return transferring stroke of the carriage or work slide 23.

40 Fig. 12 indicates the angular cammed up position of the squeegee holder 33 and its squeegee 154, and there is shown particularly in Fig. 14 a notch 167 formed in the upper portion of knock-off arm 31, which in the position shown in Fig. 12 is adapted to receive the detent 169 which extends through housing 168 and which includes a coil spring 170 normally urging said detent to the left. This thus assures that the squeegee will be maintained in its cammed up position during 45 the transferring stroke of the carriage.

50 Now at the end of the transferring stroke such as illustrated in Fig. 14 the stop 150 operatively engages the arm 31 and pivots the same to the position shown in Fig. 14, disengaging the detent 169 and at the same time causing the squeegee 154 to be cammed down into transfer position ready for the return printing movement of the work slide 23 to the right.

As shown in Figs. 11 through 15 transverse rod 60 163 is secured at 164 adjacent the outer end of trunnion rod 30 to which is secured the squeegee holder 33. Weight 165 is slidably adjustable upon the rod 163 and may be secured in position by the set screw 166. By this construction a rotary 65 thrust is delivered to shaft 30 to thereby regulate the downward pressure of the squeegee 154 with respect to the screen 41.

The vacuum bed 34 is provided to hold the work sheet in screening position however under some conditions no sheet may be delivered to the vacuum bed. In this case it would be undesirable to have the squeegee bear down upon the screen and pass over the vacuum bed, as this would result in printing material being drawn 70 thereinto. This avoided by an interference cam

which is associated with the vacuum bed as illustrated in Fig. 9 and which in the absence of a work sheet thereover will maintain a rod in the path of the squeegee knock-off arm 31 which will cam the same upwardly lifting the squeegee above the silk screen.

Referring to Fig. 9 as well as Figs. 11 through 15 there is provided a small cylindrical opening upon one side of the vacuum bed 34 which is in communication with vacuum chamber 35. Cylindrical hollow extension 160 is joined to the bed 34 for registry with said opening, and piston 162 is positioned within said opening. Piston rod 45 is joined to said piston and projects outwardly through extension 160 and by virtue of a coil spring 161 is normally maintained in the position shown in Fig. 11 i. e. in the path of squeegee actuating lever 31. When vacuum is introduced into the bed 34 immediately prior to the start of the screening stroke of the squeegee, and if a work sheet is in position upon bed 34, then said piston and rod will move inwardly under atmospheric pressure so as to be out of the path of the squeegee arm 31.

Thus the squeegee will be automatically cammed up upon the screening stroke when no sheet is upon the vacuum bed.

As shown in Fig. 11 the control panel 15 includes thereon speed control 172, operating pressure gage 173 and line pressure gage 174. Speed control 172 is connected to the valves 117 Fig. 9. Operating pressure gage 173 is shown in Fig. 9 connected with one of the pipes 25 going to cylinder 20, whereas the line pressure gage 174 is connected to the main airline 110.

Referring to Fig. 6 and Figs. 12 and 15, squeegee holder 33 is secured upon the trunnion shaft 30 and projects downwardly therefrom being bifurcated at its opposite end to cooperatively and retainingly receive throughout its width the squeegee body 155 which retains throughout a longitudinal slot at its lower end the rectangularly shaped squeegee blade 154. This blade is secured within the lower end of squeegee body 155 by the transverse screws 159, said squeegee projecting below its holder or squeegee body as shown in the drawings.

Near the squeegee blade end the body 155 has formed upon its opposite sides a plurality of equally spaced longitudinally extending grooves 156 one of which upon each side of said body is adapted to receive a corresponding projecting rib 157 Fig. 12 extending inwardly from opposite sides of the interior walls of the squeegee holder 33. Elongated slots 158 are also formed in the squeegee body 155 and are adapted to receive inwardly projecting studs from the mounting face of the squeegee holder 33.

As the screening lower edge of the squeegee 154 wears and is sharpened the squeegee body 155 can be moved down relative to the mounting ribs 157 of the squeegee holder. For wear between the spacings of the grooves 156 of the squeegee body accommodation can be made in the allowable squeegee contact angle upon the screen 41. Furthermore the body 155 is reversible so that both edges of the squeegee blade 154 can be used before sharpening. To remove or reverse said blade it is merely necessary to remove the screws 159. As shown in Fig. 15 the squeegee body 155 is retained within the squeegee holder 33 as by the studs 155'.

A squeegee sharpening device is shown in Fig. 5 of the drawings which includes the base 185 and the squeegee supporting oppositely arranged guide elements 186 and which include the inturned

ledges 187 upon which the squeegee body 155 slidably rests during sharpening of the squeegee 154. The squeegee guides are supported in parallel spaced relation to the base 185 by the links 189 which are pivotally joined to the base 185 at points 190 and pivotally joined to the guides 186 at points 191.

Adjusting shaft 192 rockably anchored at 193 within base 185 is threaded at its opposite end at 194 to adjustably engage the link 189 at 195. By rotation of member 192 in one direction or the other it is possible to regulate the height of the guides 186 relative to the base, at the same time regulating the relationship between the lower edge of squeegee 154 and the abrasive sharpening strip 198.

Said strip is arranged upon the rolls 197 which are journaled at 201 to the upright members 196 upon the base 185. Ratchets 199 engage the ratchet teeth 200 upon the rolls 197 for securing adjustably the abrasive strip relative to the squeegee 154. Thus the height of the squeegee may be regulated and furthermore a double ratchet feed is provided for the abrasive material 198. Sharpening is accomplished by drawing the squeegee body 155 back and forth through the guides 186 over the abrasive strip 198. The squeegee is guided on the interior sides and shoulders of said guides adjacent the blade, whose surfaces are parallel with the guide grooves 156 formed in the squeegee body 155. Here also the interior walls of the guides 186 have formed thereon a longitudinal rib 188 Fig. 6 which is adapted to cooperatively nest within a corresponding groove 156 in the squeegee body.

Now referring to Fig. 15 the work slide 23 is shown approximately at the end of the screening stroke just prior to the camming up of the squeegee holder 33 by the stop 153 shown in Fig. 12. Screening material by which the print is formed is piled up at 183 upon the silk screen 41 adjacent the screen frame 40, and the squeegee blade 154 dips into said material before being cammed upwardly. Thus the squeegee carries sufficient screening material for printing upon the next printing stroke of the carriage 23.

Operation

To operate the silk screen printing machine above described it is of course necessary that the shut-off valve 111 Fig. 9 be open. Also the control arm 16 upon the instrument panel must be moved to "on" position after which the operator depresses the foot pedal 130, and this starts the machine cycle.

The grippers 42 close upon the work sheet 76 which was previously properly located in pre-load position 76' Fig. 1 as by the locators 91 and 92 of Fig. 7.

The work slide 23 then moves to the right transferring the work sheet to screening position upon the vacuum bed 34. At the end of this transferring stroke the squeegee 154 is cammed down to screening position by the engagement of the cam arm 31 with respect to the stop 150, and this is illustrated in Fig. 14.

The vacuum bed is now provided with a vacuum source and the work sheet is secured thereon ready for the return screening stroke of the work slide and squeegee. However before the return screening stroke the grippers 42 release the work sheet 76, and then the work slide and the squeegee carried thereby return on the screening stroke with the squeegee 154 depressing the silk screen 41 to contact the work sheet 76.

Near the end of this screening stroke as shown in Fig. 15 the squeegee momentarily dips into the screening material 183 at the left hand side of the screen picking up screening material for the next cycle, after which it is cammed upwardly to clear the screen in the manner illustrated in Fig. 12, with the stop 153 operatively engaging the knock-off arm 31 connected with the squeegee holder 33. This completes the first cycle.

As shown in Fig. 14 the work slide 23 as it nears the end of the screening stroke to the right operates the locators 92 of Fig. 7 depressing the same so that the next work sheet 76, which was previously properly located before depression of said locators, can be properly gripped and transferred to the vacuum bed upon the next successive transferring stroke of the work slide. At the same time the forward set of grippers 42 upon the leading end of the carriage 23 or work slide engage the work sheet which has previously been printed and now transfer this work sheet to the discharge area 171 which is illustrated in Figs. 11 and 12 and which corresponds to position 76''' of Fig. 1 and Fig. 13. Position 76'' shown in Figs. 1 and 13 indicates the printing position of the work sheet 76 upon the vacuum bed 34.

The machine can be stopped at any point in the cycle by moving the operating lever 16 to the off position, and in this case and as shown in Fig. 17 this will have the effect of bleeding both of the four-way valves 107 and 108 Fig. 9.

For automatic continuous operation the foot pedal 130 may be secured in depressed position by the latch 130'.

In Fig. 9 112 indicates an oil vapor supply to the pneumatic system which is effective to lubricate the cycle valves and the cylinders shown.

Having described my invention, reference should now be had to the claims which follow for determining the scope thereof.

I claim:

1. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, and a pair of work sheet gripping elements depending from said slide for transporting a work sheet from said bed to said work sheet support under said screen.

2. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, and a pair of work sheet gripping elements depending from said slide for transporting a work sheet from said support onto said bed.

3. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a pair of work sheet gripping elements depending from the rear edge of said slide for transporting a work sheet from said bed to said work sheet support, and a second pair of work sheet gripping elements depending

from the leading edge of said slide for simultaneously transporting a work sheet from said support onto said bed.

4. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a hollow piston rod and piston secured at its ends to said bed with fluid outlets formed in said rod adjacent opposite sides of said piston, a pneumatic cylinder reciprocally mounted upon said rod and joined to said slide, said cylinder including a pair of cylinder heads at its opposite ends, each of said heads being cooperable with an outlet opening defining a pressure chamber, there being a channel in said head interconnecting said chamber and one side of said piston, and an adjustable ball relief valve in said channel adapted to open upon the building up of a predetermined pressure in said chamber.

5. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a hollow piston rod and piston secured at its ends to said bed with fluid outlets formed in said rod adjacent opposite sides of said piston, a pneumatic cylinder reciprocally mounted upon said rod and joined to said slide, said cylinder including a pair of cylinder heads at its opposite ends, each of said heads being cooperable with an outlet opening defining a pressure chamber, there being a channel in said head interconnecting said chamber and one side of said piston, and an adjustable check valve in said channel adapted to open permitting restricted exhausting of fluid from said cylinder to said pressure chamber to cushion the movement of the cylinder head relative to said piston.

6. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a pair of work sheet gripping elements depending from said slide for transporting a work sheet from said bed to said work sheet support under said screen, each gripping element including a stationary grip projecting inwardly for movement above said support and under said screen, a movable grip pivoted to said stationary grip and extending inwardly for similar movement, fluid motor means for moving said latter grip into cooperative relation with said first grip, and a coil spring interconnecting said grips to open said movable grip upon pressure release of said means.

7. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a pair of work sheet gripping elements depending from the rear edge of said slide for transporting a work sheet from said

bed to said work sheet support, and a second pair of work sheet gripping elements depending from the leading edge of said slide for simultaneously transporting a work sheet from said support onto said bed, each gripping element including a stationary grip projecting inwardly for movement above said support and under said screen, a movable grip pivoted to said stationary grip and extending inwardly for similar movement, fluid motor means for moving said latter grip into cooperative relation with said first grip, and a coil spring interconnecting said grips to open said movable grip upon pressure release of said means.

8. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a pair of work sheet gripping elements depending from said slide for transporting a work sheet from said bed to said work sheet support under said screen, each gripping element including a stationary grip projecting inwardly for movement above said support and under said screen, a movable grip pivoted to said stationary grip and extending inwardly for similar movement, fluid motor means for moving said latter grip into cooperative relation with said first grip, and a coil spring interconnecting said grips to open said movable grip upon pressure release of said means.

9. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a pair of work sheet gripping elements depending from the rear edge of said slide for transporting a work sheet from said bed to said work sheet support, a second pair of work sheet gripping elements depending from the leading edge of said slide for simultaneously transporting a work sheet from said support onto said bed, each gripping element including a stationary grip projecting inwardly for movement above said support and under said screen, a movable grip pivoted to said stationary grip and extending inwardly for similar movement, fluid motor means for moving said latter grip into cooperative relation with said first grip, and a coil spring interconnecting said grips to open said movable grip upon pressure release of said means, a source of pressure fluid, and conduits joining said source and each of said fluid motor means for simultaneously operating said gripping elements.

10. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a piston rod and piston secured at its ends to said bed, a pneumatic cylinder reciprocally mounted upon said rod and joined to said slide, a pair of work sheet gripping elements depending from said slide for transporting a work sheet from said bed to said work

sheet support under said screen, each gripping element including a fluid motor, a pressure chamber in said cylinder, and a conduit interconnecting said pressure chamber with each of said fluid motors.

11. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a piston rod and piston secured at its ends to said bed, a pneumatic cylinder reciprocally mounted upon said rod and joined to said slide, a pair of work sheet gripping elements depending from the rear edge of said slide for transporting a work sheet from said bed to said work sheet support, and a second pair of work sheet gripping elements depending from the leading edge of said slide for simultaneously transporting a work sheet from said support onto said bed, each gripping element including a fluid motor, a pressure chamber in said cylinder, and a conduit interconnecting said pressure chamber with each of said fluid motors.

12. In a silk screen printing press, a horizontal bed, a work sheet support thereon, a screen mounted upon said bed and positioned above and adjacent said support in parallel spaced relation, a reciprocal slide movably mounted upon said bed above said screen, a squeegee carried by and depending from said slide and movable upon the surface of said screen, a piston rod and piston secured at its ends to said bed, a pneumatic cylinder reciprocally mounted upon said rod and joined to said slide, a pair of work sheet gripping elements depending from said slide for transporting a work sheet from said bed to said work sheet support under said screen, each gripping element including a fluid motor, a pressure chamber in said cylinder, a conduit interconnecting said pressure chamber with each of said fluid motors, and a ball relief valve in said cylinder in communication with said pressure chamber permitting energization of said motors before actuation of said cylinder.

13. In a silk screen printing press, a horizontal bed, a work sheet supporting vacuum bed including a vacuum chamber, and a plurality of spaced outlets in the top of said bed in communication with said chamber, a vacuum source, a conduit interconnecting said source and said vacuum chamber, a reciprocal slide movably mounted upon said horizontal bed above said vacuum bed, a screen mounted upon said horizontal bed parallel to said vacuum bed, a transverse trunnion bar rockably mounted upon said slide, a squeegee mounted upon and depending from said bar for engagement with said screen, a camming arm depending transversely from one end of said bar for rocking said squeegee relative to said screen, a cylinder housing joined to said vacuum bed in communication with said vacuum chamber, a piston rod including a piston positioned through said housing, a coil spring between said piston and housing normally urging said piston rod into the path of movement of said camming arm for engagement therewith, said piston being retractable under atmospheric pressure upon the maintenance of a vacuum within said vacuum chamber.

14. In a silk screen printing press, a horizontal bed, a reciprocal slide movably mounted upon said horizontal bed, a reciprocal fluid motor upon said

bed joined to said slide, a source of pressure fluid, a fourway valve joined thereto, a pair of conduits interconnecting said valve with opposite ends of said motor, a work piece supporting vacuum bed upon said horizontal bed, a vacuum cylinder having a reciprocal piston and rod therein, a conduit interconnecting one end of said vacuum cylinder with said vacuum bed, a vacuum operating cylinder, a reciprocal piston therein joined to the vacuum cylinder piston rod, a second fourway valve joined to said source of pressure fluid, and a pair of conduits interconnecting said latter fourway valve with opposite ends of said vacuum operating cylinder.

15. In a silk screen printing press, a horizontal bed, a reciprocal slide movably mounted upon said horizontal bed, a reciprocal fluid motor upon said bed joined to said slide, a source of pressure fluid, a fourway valve joined thereto, a pair of conduits interconnecting said valve with opposite ends of said motor, a work piece supporting vacuum bed upon said horizontal bed, a vacuum cylinder having a reciprocal piston and rod therein, a conduit interconnecting one end of said vacuum cylinder with said vacuum bed, a vacuum operating cylinder, a reciprocal piston therein joined to the vacuum cylinder piston rod, a second fourway valve joined to said source of pressure fluid, and a pair of conduits interconnecting said latter fourway valve with opposite ends of said vacuum operating cylinder, said valves including spring biased valve elements therein normally directing pressure fluid to the one ends of said motor and vacuum operating cylinder, and separate valve operating conduits respectively interconnecting said source and said valves for reversing the operation thereof.

16. In a silk screen printing press, a horizontal bed, a reciprocal slide movably mounted upon said horizontal bed, a reciprocal fluid motor upon said bed joined to said slide, a source of pressure fluid, a fourway valve joined thereto, a pair of conduits interconnecting said valve with opposite ends of said motor, a work piece supporting vacuum bed upon said horizontal bed, a vacuum cylinder having a reciprocal piston and rod therein, a conduit interconnecting one end of said vacuum cylinder with said vacuum bed, a vacuum operating cylinder, a reciprocal piston therein joined to the vacuum cylinder piston rod, a second fourway valve joined to said source of pressure fluid, and a pair of conduits interconnecting said latter fourway valve with opposite ends of said vacuum operating cylinder, said valves including spring biased valve elements therein normally directing pressure fluid to the one ends of said motor and vacuum operating cylinder, separate valve operating conduits respectively interconnecting said source and said valves for reversing the operation thereof, separate pilot valves in said valve operating conduits to initiate when actuated the flow of pressure fluid therethrough to operate the respective fourway valve, and separate exhaust pilot valves in said valve operating conduits to exhaust when actuated respectively

the pressure fluid from said valve operating conduits.

17. In a silk screen printing press a horizontal bed, a reciprocal slide movably mounted upon said horizontal bed, a reciprocal fluid motor upon said bed joined to said slide, a source of pressure fluid, a fourway valve joined thereto, a pair of conduits interconnecting said valve with opposite ends of said motor, a work piece supporting vacuum bed upon said horizontal bed, a vacuum cylinder having a reciprocal piston and rod therein, a conduit interconnecting one end of said vacuum cylinder with said vacuum bed, a vacuum operating cylinder, a reciprocal piston therein joined to the vacuum cylinder piston rod, a second fourway valve joined to said source of pressure fluid, a pair of conduits interconnecting said latter fourway valve with opposite ends of said vacuum operating cylinder, and a series of pilot valves in said valve operating conduits, intermittently operable to effect automatic cyclic reversals of said fourway valves, whereby said slide is reciprocated continuously upon said bed, and vacuum is intermittently applied to said vacuum bed.

18. In a silk screen printing press, a horizontal bed, a reciprocal slide movably mounted upon said horizontal bed, a reciprocal fluid motor upon said bed joined to said slide, a source of pressure fluid, a fourway valve joined thereto, a pair of conduits interconnecting said valve with opposite ends of said motor, a work piece supporting vacuum bed upon said horizontal bed, a vacuum cylinder having a reciprocal piston and rod therein, a conduit interconnecting one end of said vacuum cylinder with said vacuum bed, a vacuum operating cylinder, a reciprocal piston therein joined to the vacuum cylinder piston rod, a second fourway valve joined to said source of pressure fluid, a pair of conduits interconnecting said latter fourway valve with opposite ends of said vacuum operating cylinder, a vacuum operated work sheet loading and pick-off devices upon said horizontal bed, and a conduit interconnecting the other end of said vacuum cylinder and said devices to intermittently energize the same.
